UNITED STATES PATENT OFFICE.

WILLIAM FRANCIS WEEKES, OF LINWOOD, PENNSYLVANIA, ASSIGNOR TO GENERAL CHEMICAL COMPANY, OF NEW YORK, N. Y., A CORPORATION OF NEW YORK.

FEEDING DEVICE FOR ROASTING-FURNACES.

1,378,068.

Specification of Letters Patent. Patented May 17, 1921.

Application filed July 29, 1919. Serial No. 314,155.

To all whom it may concern:

Be it known that I, WILLIAM FRANCIS WEEKES, a citizen of the United States, and resident of Linwood, county of Delaware, State of Pennsylvania, have invented certain new and useful Improvements in Feeding Devices for Roasting-Furnaces, of which the following is a specification.

My invention relates to furnaces of the type commonly known as Herreshoff roasting furnaces and illustrated, in one form, in the Herreshoff Patent No. 556,750 of March 24, 1896.

Such furnaces generally include a plurality of superposed hearths upon which the material being treated is progressively deposited through the medium of suitably operated rabble arms, the progression being downward and usually beginning at the uppermost hearth. When using such furnaces for certain purposes, such as for instance, in burning brimstone, it has been found desirable or necessary under certain conditions to initially deposit the material upon one of the intermediate hearths rather than upon the uppermost one. Up to the present time this operation has been laborious because it has been carried out manually.

My invention has for its object to provide an improved and simple feeding device whereby such deposit upon an intermediate hearth may be readily and automatically accomplished in an efficient and economical manner.

My invention will be fully described hereinafter and the features of novelty will be pointed out in the appended claims.

In the accompanying drawings, in which I have shown an example of my invention operatively combined with a Herreshoff furnace, Figure 1 is a plan view; Fig. 2 is a front elevation and Fig. 3 is a side elevation partly in section.

As shown in the drawings the furnace 5 is preferably cylindrical in form and is provided interiorly with a number of superposed hearths 6, alternately provided with central openings 7 and peripheral openings 8. An upright shaft 9 is suitably journaled in the furnace 5 and is rotatably driven in any convenient manner, as by means of suitably actuated bevel gears 10 and 11. This shaft 9 carries a plurality of rabble arms 12 of any well known type and located in proximity to the upper surfaces of the

hearths 6, more or less, said rabble arms 12 being constructed to feed the material progressively from one hearth to the other alternately through the openings 7 and 8 as the shaft 9 is rotated, the progression being downward. The wall of the furnace is provided with openings 13 opposite each of the hearths 6, said openings being located for instance along a single vertical line as shown by way of example in the drawings or being otherwise located in said wall, if desired; these openings 13 are closed by means of suitable closures 14 during the operation of the furnace and in all cases when open permit access to the individual hearths.

As illustrated my novel feeding device comprises a horizontal flanged receiving tray 15 carried by supports 16 which in turn are located upon a platform 17 mounted upon suitable beams 18 extending diametrically across the furnace and having their opposite ends resting upon the circular wall thereof. The exit end of the receiving tray 15, flares outwardly as shown in Fig. 1 and communicates with a flanged chute 19 which converges toward its exit end 20; the chute 19 inclines downwardly from the receiving tray 15 and has its one end fastened to one of the supports 16 and its exit end 20 extending through and resting upon the lower portion of an opening 21 formed in the wall of the furnace at the proper point.

The exit end 20 of the chute 19 is fitted into a recess 22 provided in the flaring inlet end 23 of an intermediate chute 24, the latter being supported in any suitable manner as by means of brackets 25 secured to the furnace 5; the chute 19 extends downwardly at an inclination across the furnace as shown in Fig. 2 and also extends at an inclination away from said furnace as shown in Figs. 1 and 3. The lower end of the chute 24 communicates with a hopper 26 forming part of a chute 27 having a downwardly and inwardly inclined portion 28 arranged to extend through one of the furnace openings 13 and above the hearth 6 contiguous thereto; the chute 27, with its hopper 26 and portion 28 may be supported in any convenient manner as by means of a bracket 29 secured to the wall of the furnace 5.

As shown in the illustrated example a suitably supported hopper 30 is located above and in registry with the receiving

tray 15 and serves to deliver the material thereto, said material being introduced into the hopper 30 either manually or automatically by means of suitable mechanical devices. The material may be shifted from the tray 15 to the chute 19 in any convenient manner as for instance by means of sweeps 31 mounted upon the shaft 9 which is extended upwardly through the furnace and 10 through a suitable bearing 32 for this purpose. These sweeps 31 are constructed so as to pass across the tray 15 and to sweep the material therefrom to the chute 19 as will be apparent.

15 In the illustrated example I have shown my novel feeding device arranged to deliver material to the third hearth 6 from the bottom, through the proper opening 13 which is provided for this purpose; it will be understood that by substituting the proper chute 24 the device may be readily adapted for feeding material to any of the other intermediate hearths.

In any case the material, after being deposited upon the receiving tray 15 is swept therefrom by the sweeps 31, in the proper quantity, into the chute 19 down which it passes by gravity, it being understood that the inclination of said chute 19 is greater than the angle of repose of the material in question. From the chute 19 the material passes successively into and through the chutes 24 and 27 and by finally passing through the portion 28 of the chute 27 is deposited upon one of the intermediate hearths 6, the third from the bottom in the illustration.

The feed of the material to said hearth or to any one of the others is carried on automatically and in an efficient manner without any attention other than that required to keep the hopper 30 supplied with material. The device may be quickly set up and combined with existing furnaces of the type in question and thus makes it possible to utilize a furnace intended primarily for roasting ores, for many other purposes such as roasting spent oxid, refuse from distillation of brimstone either alone or mixed with brimstone and also as a supplement to a top feed for permitting the charging of the furnace at such selected points as is desired and also to facilitate the simultaneous burning of two or more materials. The device itself is simple in construction and arrangement and requires no skilled attention when in use and at the same time avoids the manual labor heretofore required when it was desired to charge a furnace of the indicated 60 type at an intermediate point.

Another advantage present in the inven-

tion is regularity of feed giving uniform temperatures in the furnace and thus less wear and tear on the furnace as compared with charging by hand at intervals, and when feeding brimstone or its equivalent, also giving gas of uniform SO_2 content which is an advantage in sulfuric acid manufacture.

Various changes in the specific form shown and described may be made within the scope of the claims without departing from the spirit of my invention.

I claim:

1. The combination of a furnace having a plurality of superposed hearths and wall openings in registry therewith, means located upon the top of the furnace for receiving material and a plurality of co-operating chutes arranged in series and communicating with said receiving means whereby material is conducted from said receiving means and delivered through a wall opening to a hearth other than the top one.

2. The combination of a furnace having a plurality of superposed hearths and wall openings in registry therewith, a receiving tray located upon the top of said furnace, a chute carried by said furnace and inclined downwardly from said tray, means for transferring material from said tray to said chute and a plurality of individual tubular chutes located exteriorly of the furnace and communicating with said first chute and with each other whereby material is conducted from said tray and delivered through a wall opening to an intermediate hearth.

3. The combination of a furnace having a plurality of superposed hearths and wall openings in registry therewith, a rotatable vertical shaft in said furnace and extending upwardly beyond the same, rabble arms carried by said shaft, a receiving tray located upon the top of said furnace, a hopper above said tray whereby material is delivered thereto, a downwardly inclined chute having its one end in receiving relation to said tray, sweeps carried by said shaft arranged to periodically transfer material from said tray to said chute, an intermediate tubular chute located exteriorly of said furnace and arranged to receive material from said first chute and a final tubular chute located exteriorly of said furnace and arranged to receive material from said intermediate chute and conduct it through a wall opening to an intermediate hearth.

In testimony whereof I have hereunto set my hand.

WILLIAM FRANCIS WEEKES.

Witness:

NELLIE M. FINEGAN.
